STRAND TESTING

Samuel L. Ross, New Brunswick, N. J., assignor
to Johnson & Johnson, a corporation of New
Jersey

Application July 17, 1945, Serial No. 605,480

6 Claims. (Cl. 73—7)

1

This invention relates to apparatus for testing the abrasion resistance of strands.

The utility and durability of fibrous articles, such as thread, yarn, and various kinds of textile fabrics depends upon the inherent resistance to abrasion of the yarns of which the article is composed, which in turn depends upon the inherent resistance to abrasion of the individual fibers making up the yarns. Consequently, in order to determine in advance the durability of fibrous articles made from various materials, it has been proposed to test the abrasion resistance of the yarns before constructing the article in order to assist in the selection of the most desirable materials. Devices which have come to my attention for testing the abrasion resistance of yarns have the disadvantage that they do not accurately simulate the conditions of actual use of many fibrous materials and in particular they do not abrade the yarns, or the individual fibers, or monofilaments of which the yarns are composed, across the length of the fiber or monofilament and do not properly compress the fibers or monofilaments while abrading the yarn.

Accordingly it is an object of my invention to provide a simple and effective device for testing yarns, monofilaments and the like by subjecting the yarns, for example, to a combination of tension and transverse abrasion which accurately simulates the forces applied to the yarns in many instances of actual use.

Another object of the invention is to provide a simple apparatus which can be set in operation and thereafter automatically test and record the characteristics of the fiber without further attention.

The single figure of the accompanying drawing is a perspective view, partly diagrammatic, of one form of apparatus embodying my invention.

The invention is illustrated as applied to a device which is particularly adapted to testing dental floss and for simulating the conditions under which dental floss is used, although this identical apparatus is equally well suited for the testing of other fibers and yarns for other purposes.

Referring to the drawing, two opposed friction members 10 and 12 are suitably mounted and supported to be resiliently urged in contact with each other, and a fibrous strand 14 is so supported that it can be moved back and forth between the friction members. As illustrated the friction members have surfaces which converge toward the point of contact and simulate the cusps of the crown of a tooth, having round-

2

ed polished surfaces to be engaged by the strand. The friction members may be of any suitable material, such as, hardened and polished steel or if desired actual teeth can be used. The term "tooth cusp" as herein used is intended to cover either a natural tooth or a simulated tooth cusp.

The member 12 is mounted on a stationary support and the member 10 is mounted on a movable support 16 which may slide in guides 18 and is resiliently urged against the member 12 by the weight of the support 16 which may be suitably adjusted by any desired number of weights 20, 22, and 24. A bracket 26, having an opening 27, supports an arm 28 having an opening 30 through which openings the strand to be tested passes. One end of the strand is anchored in any suitable manner to a slide 32 on a guide rod 34 supported in any suitable manner as by supports 36 and 38. The tension of the strand is adjusted by any suitable number of weights 40 and 42 supported on a rod 44 which is supported by the other end of the strand. When the strand is mounted, as shown, the slide 32 is moved back and forth on the rod 34 causing the strand, while held under tension, to pass between the cusps 10 and 12 which both compress the strand and abrade it in a direction transverse to its length. It has been found that the number of times a strand withstands passage between the cusps 10 and 12 is an indication of its abrasion resistance and of its durability in various kinds of structures and fabrics.

It will be appreciated that the tension of the strand can be regulated by the weights 40 and 42, the compression can be regulated by the weights 20 to 24, and the friction or abrasive force can be regulated by selection of the material of which the cusps 10 and 12 are formed, and the shape of the compression members can be varied to simulate a wide variety of actual service conditions. For example, in testing textile yarns, the cusps can be made of porcelain, wood, metal, or other material which performs representative tests.

It has been found that the number of times a single strand or yarn will pass between a given pair of compression members under given conditions furnishes a more accurate index of the wearing qualities of certain fabrics than any other means of testing which has come to my attention. Consequently the term "strand" or "fibrous strand" as used herein is intended to include an individual fiber, a monofilament of syn-

thetic material, and a yarn or thread twisted or braided from individual fibers.

Preferably the slide 32 is repeatedly operated by a pitman 46 driven by any suitable motor 48, for example an electric motor having a reduction gear. The motor is started and stopped by a switch 50 operated by a switch arm 52 connected to the weight rod 44 so that when the strand breaks in test the motor is automatically stopped. Any suitable counter 54 may be mounted in the path of the slide 32 to register the number of times the strand passes between the abrasion members.

I claim as my invention:

1. Apparatus for testing the abrasion resistance of a fibrous strand comprising in combination means for holding a strand, a pair of opposed members including a tooth cusp adapted to compress the strand and to yieldingly resist passage of the strand between said members and means for effecting relative movement between the strand and the members in a direction transverse to the length of the strand to cause the strand to be compressed and to pass between the members while under tension.

2. Apparatus for testing the abrasion resistance of a fibrous strand comprising in combination means for holding a strand, a pair of opposed members including a tooth cusp adapted to compress the strand, means for resiliently urging the members toward one another to yieldingly resist passage of the strand between said members, and means for effecting relative movement between the strand and the members in a direction transverse to the length of the strand to cause the strand to be compressed and to pass between the members while under tension.

3. Apparatus for testing the abrasion resistance of a fibrous strand comprising in combination means for holding a strand, a pair of opposed members adapted to compress the strand, one of said members being a tooth cusp, means for resiliently urging the members toward each other, and means for moving one end of the strand in a direction transverse to its length to cause the strand to pass between the members while the strand is held under tension.

4. Apparatus for testing the abrasion resistance of a fibrous strand comprising in combination means for holding a strand, a pair of opposed

members adapted to compress the strand, one of said members being a tooth cusp, means for resiliently urging the members toward each other, and means for moving one end of the strand in a direction transverse to its length to cause the strand to pass between the members while the strand is held under tension, said holding means being adapted to maintain the strand tension substantially constant during said movement.

5. Apparatus for testing the abrasion resistance of fibrous strands comprising in combination means for holding a strand, a pair of opposed members adapted frictionally to engage opposite sides of the strand, means for yieldingly urging the members toward each other to compress the strand and to yieldingly resist passage of the strand between the members, and means for repeatedly passing the strand between the members in a direction transverse to the length of the strand to compress and abrade the strand under tension.

6. Apparatus for testing the abrasion resistance of fibrous strands comprising in combination means for holding a strand, a pair of opposed members adapted to engage opposite sides of the strand, means for yieldingly urging the members toward each other to yieldingly resist passage of the strand between the members, the members having converging surfaces adapted to progressively compress the strand when the strand is passed between them, and means for passing the strand between the members in a direction transverse to the length of the strand progressively to compress and abrade the strand while under tension.
